UNITED STATES PATENT OFFICE.

CHARLES D. MENEELY, OF ALBANY, AND JOHN GIBBONS, OF WEST TROY,
ASSIGNORS TO THE MENEELY BEARING COMPANY, OF WEST TROY, NEW
YORK.

ROLLER-BEARING.

SPECIFICATION forming part of Letters Patent No. 400,471, dated April 2, 1889.

Application filed November 19, 1888. Serial No. 291,197. (No model.)

To all whom it may concern:

Be it known that we, CHARLES D. MENEELY,
of the city of Albany, county of Albany, and
State of New York, and JOHN GIBBONS, of
the village of West Troy, county and State
aforesaid, have jointly invented new and useful
Improvements in Roller-Bearings, of which
the following is a specification.

Our invention relates to improvements
upon that class of axle-bearings which are
made with friction-rollers having journaled
ends and intermediately placed separating-
rollers that are arranged to engage with the
friction-roller journals and run upon an in-
terior track, with a guide-ring encompassing
said separating-rollers or "equalizers" and
the friction-rollers; and our improvement
thereon has for its object a new construction
and arrangement of the friction-rollers and
separating-rollers encompassing ring and in-
ner track, to better adapt this class of devices
to be run upon the axles of railway passenger-
cars without lubricant, and to combine with
these parts so improved and arranged a
means to take-up and sustain the end-thrust
of the axle without frictional engagement
and the necessity of lubricant.

To take up the end-thrust as heretofore
made, this class of roller-bearings has been
constructed to contain two guide-rings that
project inwardly from the inner surface of
the bearing-box, so as to enter and engage
with grooves made to encircle the friction-
rollers at each end, wherein the rings make a
frictional engagement with the sides of the
roller-grooves, but the production of which
grooves and their engagement with the rings
necessitated the use of lubricant, and reduced
the bearing-surface of the friction-rollers to
such an extent that it weakened their ca-
pacity to resist a crushing-strain and unfitted
them for use in connection with the axles of
railway passenger-cars. In this older class of
roller-bearings there was also used upon and
secured to the outer end of the axle a flat
circular disk or plate that turned with the
axle in a flat circular chamber, against the
outer surface of which interior chamber the
disk or plate abutted to take up the end-

thrust of the axle, and this construction to 50
be operated successfully required lubricant.
To improve upon this means to take up the
end-thrust of the axle is one of the objects
of our invention, and this we accomplish by
projecting the axle beyond the friction-roll- 55
ers and make an encircling groove therein
with a coinciding groove in the axle-cap, so
as to form in the combined axle and cap a
circular tube-form passage-way in which is
placed a single ball that turns therein to take 60
up the end-thrust, and as thus made and ar-
ranged the said ball performs its function
without lubricant.

To improve and make better adapted to
stand the heavy crushing-strain of railway 65
passenger-car axles, we construct the separat-
ing-rollers or equalizers of this class of de-
vices so that they shall run upon the inside
tracks on both sides of the groove formed in
said rollers, instead of at one side of said 70
groove, and so that where said separating-
rollers are arranged at each end of the bear-
ing between each two of the friction-roller
journals they shall be operated by the latter
to run independently and without any con- 75
nection with each other. When these sepa-
rating-rollers or equalizers are connected by
an intermediate bar, or when the separating-
rollers extend from end to end of the bearing,
they take up room and from necessity 80
reduce and limit the number of friction-rollers,
so as to unfit the bearing for use in con-
nection with the axles of railway passenger-
cars, in which more supporting capacity is
required to resist and sustain the heavy crush- 85
ing-strain upon the rollers.

Accompanying this specification to form a
part of it there are five plates of drawings
containing eight figures illustrating our in-
vention, with the same designation of parts 90
by letter-reference used in all of them.

Of these illustrations, Figure 1 shows a lon-
gitudinal central vertical section of the jour-
nal-box and its end cap parts, the inside tracks
for the separating-rollers, and the ring which 95
encompasses the friction-roller journals and
the separating-rollers, with two of the fric-
tion-rollers and a separating-roller shown as

back of the journals of the friction-rollers, and with the axle shown also in side elevation. Fig. 2 shows a side elevation of our improved bearing with a vertically-divided half 5 of the journal-box removed, the cap shown in vertical section and the end-thrust ball within the tube-form passage shown in elevation. Fig. 3 is a vertical section taken on the line x^x of Fig. 1. Fig. 4 is a side elevation of one 10 of the friction-rollers, illustrated as removed from the bearing-box. Fig. 5 is a side elevation of one of the separating-rollers, shown as removed from the bearing-box. Fig. 6 is a 15 section of the axle-cap, showing the circular groove made therein, which, in connection with a like groove made in the axle, produces the circular tube-form passage-way for the end-thrust ball. Fig. 7 shows a plan view of one of the inside tracks on which the separating-rollers run. Fig. 8 shows a section 20 taken on the line $x^2 x^2$ of Fig. 7.

The several parts of the mechanism thus illustrated are designated by letter-reference, and the function of the parts is described as 25 follows:

25 The letter A designates the axle; B, the bearing-box; C, the outer end cap of the axle-box, made in two parts, $c^3 c^4$, that are connected by bolts b' and lugs L.

30 The letters R' designate the friction-rollers, which at each of their ends are made with journals J, having a less diameter than the rollers proper. Each of these journals J is made with an encircling groove, g' .

35 The letters R² designate the separating-rollers or equalizers, which are made to have a length that is a little less than the journals of the friction-rollers, and each of these separating-rollers is constructed with an encircling 40 groove, g^2 .

45 The letter T designates a track formed within the bearing-box at each end of the latter, so as to encompass the axle, but not to come in contact with it. Each of these track parts is projected inwardly from the end of the bearing-box, so as to be a little shorter than the journals of the friction-rollers. The track part at the outer end of the axle is formed on the inside of the cap part c^4 , and 50 the track part on the inner end of the bearing-box is held in position by the sleeve S.

55 The letter O designates a guide-ring, of which there is one at each end of the bearing. These rings are made to be passed on over the separating-rollers and to run in the grooves made in the latter.

60 The parts thus described operate connectedly as follows: The friction-rollers R' are placed at intervals between the inner surface of the bearing-box and the exterior surface of the axle at such distance apart as to avoid contact, with one of the separating-rollers R² at each end of the bearing between each two of the friction-roller journals, so as to engage 65 with the latter and to run on the end track parts at each side of the encircling groove

made in the bearing-face of said separating-rollers, and to turn with the same direction of axial rotation as the axle. The rings O, being passed on over the separating-rollers at 70 each end of the bearing and placed within the grooves of the separating-rollers at their outer surface, serve to keep the separating-rollers in position and in engagement with the friction-roller journals, so that the latter 75 and the separating-rollers act connectedly. The groove made in the journals of the friction-rollers is merely for the passage of the rings without contact therewith. The diameters of the friction-roller journals are so proportioned relatively to the diameters of the separating-rollers that the separating-rollers shall make one circuit of the inside track while the friction-rollers are making one complete circuit of the interior of the bearing-box. 80

The letter G' designates a groove made in the outer end of the axle, where projecting beyond the journal-box proper, and G² a circular groove correspondingly made in the 90 cap parts $c^3 c^4$, so that when the cap parts are connected with each other and to the journal-box there is formed in the combined cap and axle the circular tube-form passage P, one sectional half of which is made in the cap 95 parts and the other half in the axle.

The letter B⁴ designates a ball having a diameter a little less than the cross-area of the tube-form passage P, which ball is placed in the latter. As thus arranged and constructed, 100 when the end-thrust of the axle occurs this ball rotates in a direction that is coincident with the direction of the thrust-impulse, so as to take up the latter by partly turning in the passage P, while the friction-roller, separating-rollers, and rings move together and 105 connectedly with the axle.

We are aware that a groove has been made in an axle and combined cap where the axle projected beyond the bearing-box, as in the 110 Letters Patent to Halloway of January 3, 1860, and in which a series of balls were used in such a circular passage, and where the balls would be in contact with each other and require lubricant that was arranged to be supplied by a passage-way through the cap. By using but one ball instead of several, the single ball is free to rest in the bottom of the passage from the action of gravity and where it will take up the end-thrust, as before described, and run without lubricant, which could not occur were several balls used instead of one. 115

Having thus described our invention, what we claim, and desire to secure by Letters Patent, is—

1. The combination, with a car-axle and an axle-box, of anti-friction rollers having end journal-bearings smaller than the body of the rollers and formed with annular grooves in 120 said bearings, interior tube-form tracks surrounding the axle at each end, separating-

rollers formed with annular grooves and arranged at each end of the anti-friction rollers between the journal ends of the same, and a guide-ring arranged circumferentially about 5 the journal ends of the anti-friction rollers and the separating-rollers and within the grooves in the same, substantially as described.

2. The combination, with a bearing-box that 10 is made with an interior track at each end, and constructed with a cap at its outer end containing interiorly an encircling concave groove, substantially as described, of an axle made with an encircling concave groove at its 15 outer end arranged to be in line with and correspond in reversed and opposite concavity with the groove made in the cap, an end-thrust ball arranged within the coincidently-made grooves of the cap and axle, friction-rollers 20 having grooved and journaled ends arranged between the inner surface of said bearing-box and axle, a separating-roller having a grooved roller-face arranged at each end of the bearing between each two of the friction-roller 25 journals and the adjacent end track, and a ring made to encompass said separating-rollers and to be within the grooves thereof, substantially in the manner as and for the purposes set forth.

3. The combination, with the axle A, made 30 with the encircling-grooves G', of the bearing-box B, made with the cap C, having the interior encircling-groove, G², and the interior end tracks, T T, the end-thrust ball, B⁴, arranged within the coincidently-placed grooves 35 of the axle and bearing box cap, the friction-rollers R', made with end journals, J, arranged between said axle and bearing box, and the separating-rollers R², each made with the groove g², with one of said separating- 40 rollers arranged between each two of the friction-roller journals, and the adjacent inside track at each end of the bearing, and the rings O at each end of the bearing within the grooves of the separating-rollers, substantially 45 in the manner as and for the purposes set forth.

Signed at Troy, New York, this 15th day of October, 1888, and in the presence of the two witnesses whose names are hereto written.
